UNITED STATES PATENT OFFICE.

WARREN B. WINTERS, OF STEPHENVILLE, TEXAS.

METER FOR TYPE-WRITERS.

1,114,838.

Specification of Letters Patent. Patented Oct. 27, 1914.

Application filed September 15, 1913. Serial No. 789,860.

To all whom it may concern:

Be it known that I, WARREN B. WINTERS, a citizen of the United States, residing at Stephenville, in the county of Erath and State of Texas, have invented certain new and useful Improvements in Meters for Type-Writers; and I do hereby declare the following to be a full, clear, and exact description of the invention "such as will enable others skilled in the art to which it appertains to make and use the same, reference being had to the accompanying drawings, and to the letters and figures of reference marks thereon, which form a part of this specification. 15. This invention relates to new and useful improvements in word meters for typewriters.

The object in view is to produce a simple and efficient device of this nature having various details of construction and arrangements of parts which will be hereinafter fully described and then specifically defined in the appended claims.

My invention is illustrated in the accompanying drawings in which—

Figure 1 is a side elevation showing the application of the invention to the frame of a typewriter. Fig. 2 is a similar view showing the parts which have been actuated by the depression of a key lever, and Fig. 3 is a transverse section parts being shown in top plan view.

Reference now being had to the details of the drawings by letter, A designates the frame of a typewriter having key levers B and spacing lever C, only one of which key levers being illustrated in the drawings as sufficient to illustrate the operation of the invention. A shaft D is mounted in apertures in the opposite sides of the frame of the typewriter and has fixed to the ends thereof the two bars designated respectively by letters E and E'. A second shaft designated by F is connected to the bars E and E' and has a slight vertical play in the slots H formed in the opposite sides of the frame. A rod designated by K is fastened at its lower end to the bar E and its upper end is pivotally connected to an arm N of a word meter M. The said bar E has an upwardly extending portion E' near its free end which terminates in a hook O having an inclined face O' and a flat top P, and spring J fastened at one end to the bar at its other end to the frame and tends to normally hold the bar E at its highest limit or in the position

shown in Fig. 1 of the drawings. A hook designated by R is pivotally mounted upon a pin R' and is adapted to engage over the flat top P upon the bar E to hold the latter in the position shown in Fig. 2 of the drawings after the key lever has been depressed. A coiled spring designated by I is fastened at one end to the hook R, at its other end to the frame of the typewriter, and the purpose of said spring I is to normally hold the hook R in the position shown in Fig. 2 of the drawings after the bar E has been depressed and in which position the upper laterally projecting end S of the hook R will engage between the teeth of the star wheel T which is fixed to the shaft T' and journaled in the frame of the typewriter. Said hook R has an angled end Q shown clearly in Fig. 3 of the drawings and which extends underneath the spacing bar and in the path of the same. Said shaft T' has fixed thereto a pinion wheel T² which is in mesh with the gear wheel T³ journaled upon the stub shaft T⁴ on the frame of the typewriter.

The operation of my invention will be readily understood and is as follows: When the key lever B is depressed the shaft F will be moved downward and with it the bar E, putting the spring J under tension and drawing down upon the rod K, which in turn will pull down the arm N of the meter. As the inclined edge O' of the bar E comes in contact with the inclined edge of the hook, the latter will be swung upon its pivot, 90 throwing itself over the angled end S. As the flat top P of the bar E passes below the hook the coiled spring I will cause said hook R to be moved from the position shown in Fig. 1 to the position shown in Fig. 2, in 95 which latter position the hook will engage over the flat top P and hold the bar E depressed. The lateral projection S upon the hook R will be thrown between the fingers of the star wheel and hold the same from 100 rotation until after the letter has been registered. The depression of the spacing bar, as it comes in contact with the angled end Q of the hook R will cause the latter to tilt under tension of the spring I and disengage 105 the hook from the flattened end of the bar E, thus allowing the coiled spring J to return the bar E to its normal position and push upward upon the rod K which, through its connection with the meter, will cause the 110 letter to be registered. This operation may be continued until the carriage of the type-

writer reaches its limit in one direction. When the last letter has been printed at the end of a line, and the hook R is in the position shown in Fig. 2, and when it is not desired to actuate the spacing member, the bar E may be released by the carriage turning the wheels T' and T² which latter movement will cause the shaft T' to rotate and throw the upper angled end of the hook R out of the path of the fingers of the star wheel which will allow the bar E to be returned to its normal position and effect the registration of the letter.

By the provision of an apparatus made as shown and described, it will be noted that a simple and efficient mechanism is afforded whereby every time a key lever is depressed and a spacing member actuated, a registration will be effected and also a registration produced without the depression of a spacing member when the carriage is returned to its starting position.

What I claim to be new is:

1. A word meter for typewriters comprising, in combination with the frame of a typewriter having key spacing levers, a meter and spring-pressed lever mounted upon the frame of the typewriter and having pivotal connection with the meter, said lever having its free end angled and upturned, a spring-actuated angle lever pivotally mounted upon the frame of the machine and having an angled arm which extends underneath the spacing lever and its other arm provided with a hook, a spring connected at one end to the frame and the other end to said hook carrying arm, the hook co-

operating with the upwardly turned end of said meter operating lever, said angled lever having a portion extending above said hook and angled at its end, a star wheel engaged by said angled end, and a gear wheel and connections between the same and the star wheel, as set forth.

2. A meter for typewriters comprising, in combination with the frame of a typewriter having series of key levers and spacing member mounted thereon, a meter, a spring-pressed lever pivotally mounted on the machine and having pivotal rod connections with the meter, the free end of said lever being upwardly turned and having a flat top and a lateral projection which is inclined upon its edge, an angle lever pivotally mounted upon the frame and having an angle lever extending underneath the spacing member, and a hook projecting from one edge which is adapted to engage the flat part of the upturned portion of said spring-actuated lever, while the inclined edge with the lateral projection engages the edge of the hook carrying arm of said lever, the upper end of the arm of the lever extending laterally, a star wheel adapted to be engaged by said angled end of the lever, gear mechanism and connections between the same and the star wheel, as set forth.

In testimony whereof I have hereunto affixed my signature in the presence of two witnesses.

WARREN B. WINTERS.
